Fig. 4

Fig. 5

Fig. 6

Fig. 7

FIG. 1 is a side perspective view of a tufting machine clip showing our new design;

FIG. 2 is a top plan view thereof;

FIG. 3 is a side elevational view;

FIG. 4 is an edge view taken from the right of FIG. 3;

FIG. 5 is an elevational view of the other side of FIG. 3;

FIG. 6 is an edge view taken from the left of FIG. 3; and

FIG. 7 is a bottom plan view of the tufting machine clip.

I claim:

The ornamental design for tufting machine clip, as shown.
